MACHINE FOR SURFACE FINISHING ACTION
ON MATERIALS

Ernest Freud, Hartford, Conn.

Application February 7, 1945, Serial No. 576,637

3 Claims. (Cl. 51—90)

1

This invention relates to the class of devices for finishing highly polished surfaces on material, such as marble, granite, and the like, and an object of my invention, among others, is to obtain a very rapid action of a highly abrasive material, as Carborundum, upon the surfaces of objects being operated upon so that a satisfactory finish may be given to the surfaces in a particularly rapid and efficient manner.

One form of a device embodying my invention and in the construction and use of which the objects herein set out, as well as others, may be attained is illustrated in the accompanying drawings, in which—

Figure 1 is a plan view of a machine embodying my invention.

Figure 2 is a view in vertical section through the same.

I have found that in imparting a final finish to surfaces, particularly different kinds of stone, as granite, marble and the like, the best results are obtained if a highly abrasive material, such as Carborundum, is employed and which should be applied at a high rate of speed of the device for making the application as this will produce what may be termed a combined abrasive, cutting, buffing, and polishing effect. Such a machine is shown in the accompanying drawings in which the device is supported by an arm 5 pivotally attached to a standard or post of any suitable construction sufficient to enable the arm to have a pivotal action around said support, such support not being shown herein. A shaft 6 is rotatably mounted in the arm 5 and has a pulley 7 to receive a belt 8 extending from any suitable source of power which may be supported by the post hereinbefore mentioned and in a manner that will be readily understood. The structure thus described is that of a well-known and standard granite polishing unit in which arm 5 is pivotally mounted (not shown) to thereby permit a dirigible effect to the polishing unit carried by the arm. In such structures the arm 8a shown in Fig. 2, serves as a convenient element, readily accessible to the workman, for moving arm 5 on its dirigible pivot, carrying with it the polishing unit which is carried by the end zone of the arm and driven from the power source through belt 8, pulley 7 and shaft 6.

A rod 9 extends downwardly from the arm 5 and supports a bevel gear 10 of large diameter as compared with the other parts of the machine. The shaft 6 has one member 11 of a universal joint secured thereto, the handle 8a being journaled thereon and a second member 12 of said

2

joint is pivotally attached to said first member, the pivotal connection of said members being in transverse directions. A shank 13 extending from the member 12 of the universal joint rigidly supports a plate 14 upon which a plurality of connecting shafts 15 (four in the present instance) are journaled, each of these shafts mounting a bevel pinion 16 secured to an abrasive wheel 17 coated with an abrasive, preferably Carborundum.

As indicated in Fig. 2, the diameter of gear 10 is many times that of the gears 16. In practice, I prefer to make the ratio between gear 10 and gears 16 approximately 10:1 so far as the R. P. M. of shaft 6 and that of gears 16 is concerned; since gear 10 is held from rotation by the arm 9, the planetary movements of the abrasive formations 17, as carried by the plate 14, will produce such ratio as the gears 16 traverse gear 10. I have found that with such ratio, a rotation of shaft 6 at 200 R. P. M., will produce a rotation of gears 16 at about 2000 R. P. M.; if the speed of shaft 6 be speeded up while that of gears 16 is unchanged or reduced, there is a considerable loss of efficiency in the apparatus, while a reduction in the speed of shaft 6 materially below the 200 R. P. M., tends to create deep unequal grooves on the surface.

These speeds are approximate, and do not represent the actual speed conditions, as will be apparent, by considering the peripheral speeds. For instance, the diameter of gear 10 is such as to locate formations 17 a considerable distance from the axis of rotation of plate 14; hence, the distance of advance of formation 17 per unit of time is materially increased, thus permitting the use of the lower speed of shaft 6 and plate 14. Likewise, the diameter of each formation 17 is materially greater than that of its gear 16, so that the peripheral speed of each of the formations 17 is increased in accord with the length of the radius of the formation.

Since the axis of each of the formations 17 extends horizontally, with the cross-sectional contour of the formation as circular and located above the surface being finished, it will be understood that such surface is tangential to the contour of the formation and thus presents the characteristics of a line contact with the surface at any point of its revolution, and since the outer surface of the formation is preferably formed of Carborundum, it can be understood, that the high peripheral speed of the formation combined with the materially slower advance of the formation in its planetary path, produces an abrading action that tends to simulate the cutting effect pro-

duced by a milling cutter—in other words, the abrading action in the present invention is of the "milling cutting" type in which the cutting surface moves at high speed while traversing the work at a materially lower speed, the ratios named indicating somewhat of the effect produced—a materially lower ratio does not produce the result, since a speeding up of the drive shaft to secure the necessary speed for milling cutting by the formation 17, would then set up a very inefficient planetary speed, while a reduction of the latter to provide efficiency would prevent development of the milling cutting effect of the formations, since the resultant speed is insufficient to produce such effects.

While the invention is adapted for use in connection with various hard materials, such as metals, granites, hard stones, and the like, the invention is designed more particularly for the finishing of the surfaces of granite, hard stone and similar materials in which the finishing normally is of the polishing type, the machine of the drawings, above the universal joint 11 being a machine of this type, the unit which presents the present invention being readily secured thereto.

The structure is such that by mounting the several parts connecting the driving mechanism with the driven members or abrasive wheels 17 a very high surface velocity is imparted to said wheels and with such wheels coated with Carborundum an extremely satisfactory finish is imparted to surfaces as stone of different character being finished, and it is found that this high velocity of the surface of the abrasive wheel with the particular abrasive as Carborundum produces results not heretofore attained in machines used for this purpose.

I claim:

1. A surface finishing machine of the character described comprising a supporting arm, a driving shaft rotatable in said arm on a vertical axis, a supporting plate depending from and connected to said shaft by a universal joint, a plurality of horizontal shafts carried by said supporting plate for rotation on a horizontal axis, a pinion on each of said horizontal shafts for driving the same, an abrasive wheel on each of said horizontal shafts, a stationary gear co-axial with said supporting plate, and means connecting said gear with said supporting arm to prevent rotation thereof; the said stationary gear being substantially greater in diameter than the pinions on said horizontal shafts for causing rotation of said pinions at a ratio of approximately ten revolutions of said pinions for each revolution of said supporting plate.

2. A surface finishing machine of the character described comprising a supporting arm, a driving shaft rotatable in said arm on a vertical axis, a disk carried by said driving shaft and disposed horizontally thereto, a universal joint

connected to said shaft and including a member secured to said disk for rotating the same with said shaft, a plurality of horizontal shafts carried by said disk and rotatable thereon on a horizontal axis, each of said horizontal shafts having an abrasive wheel secured thereto and a pinion for rotating said abrasive wheel, a gear of large diameter relatively to said pinions co-axial with said member of the universal joint and in mesh with said pinions, a connection between said gear and said arm for preventing rotation of the gear, and means for rotating said driving shaft to cause rotation of said disk through said gear by the said member of the universal joint for carrying the abrasive wheel around a vertical axis over a surface being finished while the said wheels are rotated by the pinions as they are carried around the stationary driving gear; the ratio between the drive gear and the pinions being approximately ten to one whereby the said wheels will rotate approximately ten revolutions for each rotation of said drive shaft.

3. A surface finishing machine of the character described comprising a supporting arm, a driving shaft rotatable in said arm on a vertical axis, a universal joint comprising a driving member secured to said shaft and a driven member operatively connected with said driving member to swing in a plane transverse thereto, a supporting plate supported by and movable with the said driven member, a large stationary bevel gear co-axial with said driven member of the universal joint and carried thereby above said supporting plate, a connection between said bevel gear and supporting arm for preventing rotation of said bevel gear, and a plurality of shafts journaled on said supporting plate for rotation on a horizontal axis; each of said horizontal shafts having an abrasive wheel secured thereto and a pinion in mesh with said large bevel gear.
